(57) **CLAIM**

The design for coffee machine, substantially as shown in the accompanying drawings.

DESCRIPTION

FIG. 1 is a top plan view of a coffee machine showing my new design;

FIG. 2 is a front view thereof;

FIG. 3 is a right side view thereof;

FIG. 4 is a left side view thereof;

FIG. 5 is a rear view thereof;

FIG. 6 is a bottom view thereof; and,

FIG. 7 is a perspective view thereof.

Features shown in broken lines show environmental structure and form no part of the claimed design.
